CONTROL DEVICE

Earnest J. Dillman, Detroit, Mich., assignor to
 Detroit Lubricator Company, Detroit, Mich., a
 corporation of Michigan

Original application December 12, 1930, Serial
 No. 501,927. Patent No. 1,992,155, dated Feb-
 ruary 19, 1935. Divided and this application
 July 27, 1934, Serial No. 737,288

10 Claims. (Cl. 200—140)

My invention relates to new and useful improvements in control devices, and more particularly to a device for automatically controlling a motor means, such, for example, as the fan motor of a unit heater system.

An object of my invention is to provide a control means which is automatically movable between predetermined limits, and which has means operable thereon in response to a predetermined condition to maintain the control means at one limit of movement.

Another object is to provide a control means which is normally operable between limits by automatic means in response to predetermined conditions, and which has means operable in response to a predetermined condition to move the control means toward one of its limits irrespective of operation of the automatic means.

Another object is to provide a control means for a unit heater which is normally operable to control the unit heater fan means, and having means responsive to the unit heater temperature and operable on the control means to prevent control thereby of the fan means.

The invention consists in the improved construction and combination of parts, to be more fully described hereinafter, and the novelty of which will be particularly pointed out and distinctly claimed.

In the accompanying drawing, to be taken as a part of this specification, I have fully and clearly illustrated a preferred embodiment of my invention, in which drawing—

Figure 1 is a view in front elevation of a unit heater showing my control device applied thereto;

Fig. 2 is an enlarged detail view, partly in section, looking from right to left of Fig. 1 and showing the control device;

Fig. 3 is a detail view on the line 3—3 of Fig. 2, and

Fig. 4 is a detail view on the line 4—4 of Fig. 2.

Referring to the drawing by characters of reference, I designates generally the casing of a unit heater, preferably having its underside or bottom open to provide an inlet for circulation of air through the casing and having conduit or duct members 2 communicating with the interior of the casing and supported on the top casing wall to provide air outlets. Within the casing are air circulating means 3, preferably rotary fans of the squirrel cage type which draw air in through the open bottom of the casing and discharge the air through the members 2, and which are mounted on a drive shaft 4 journaled in the end or side walls of the casing. Also within the casing below

the fan means is a heat transfer element 5 for varying the sensible heat of the air flowing through the casing, and which is preferably a heating means such as a radiator or the like having a conduit for conveying a heating medium 5 such as steam thereto and condensate and steam therefrom. The conduit comprises an inlet pipe 6 and an outlet pipe 7, which pipes extend through the casing walls, preferably at the ends thereof, beneath the shaft 4. Fixed to the end wall 8 external of the casing, is a supporting bracket or member 9 on which is mounted a fan driving means 10, preferably an electric motor, which is connected to the end of shaft 4 which projects through wall 8. Secured to wall 8 external of the casing and below the element 5, is my control device 11 which controls the motor 10 and therefore the operation of the fan means 3.

The device 11 comprises a control means 12, preferably an electric switch of the mercury tube type, in which a globule of mercury enclosed in a sealed glass tube is operable to make and break contact, upon tilting or rocking of the tube, with terminals which extend into the tube. The means 12 is carried by a clip member 13 fixed to a carrier member 14 having downward extending end flanges 15, 16. Extending through the flanges 15, 16 is a pin or shaft 17 on which the means 12 is fulcrumed for rocking or tilting movement between predetermined limits. The shaft 17 is secured, as at 18, in the rear wall 19 of a casing or housing 20 which encloses the means 12. Within casing 20 is a vertically movable lever means 21 fulcrumed at one end in the end casing wall 22 and terminating at its free end beneath the shaft 17 in a substantially vertical, laterally extending portion 23 (Fig. 4) having a nut member 24 secured thereto and through which and the portion 23 is adjustably threaded a screw member 25 having a conical end 26. Projecting from the other casing end wall 27 is a supporting abutment 28 between which and the screw end 26 is a resilient means 29, preferably a coil spring, held under compression. Bearing at one end against the casing top wall 30 is a resilient means 31, preferably a coil spring, held under compression and bearing at its lower end against the top face of lever means 21. The spring means 29 and 31 which are adjustable, act conjointly to resist upward movement of the lever means and to determine the upward force required to lift the lever means 21 and serve on decrease of the lever lifting force to move the lever means 21 downward. The lifting force for the lever means 21 is provided by a power element 32 which is secured to

the underside of the casing bottom wall 33 and which has a reciprocable plunger 34 extending upward through wall 33 into engagement with the underside of lever means 21 directly beneath the 5 spring means 31. The element 32 preferably comprises a hermetically sealed bulb or container having a resilient wall to which the lower end of plunger 34 is connected, and containing a charge of volatile liquid, such that element 32 is a temperature responsive means or thermostat responsive to the temperature of the air outside of the casing 1. The element 32 and spring means 29, 31 comprise an automatic operating means for the switch tube 12. In line with the element 32 10 the heater casing end wall 8 is provided with an inlet aperture 35 so that the element 32 is directly responsive to the temperature of the air being drawn into the casing 1, which air has circulated through the space to be heated. The carrier 15 member flange 16 has an operating arm 36 which extends substantially directly over and above the free end of lever portion 23. Pivoted to and depending from arm 36 is a link or rod member 37 having its lower end slotted, as at 38. The free 20 end of portion 23 is reduced to provide a pin member 39 which extends into the slot 38. Below the slot 38 the link 37 has an aperture 40 which receives one end of a spring member 41 which is wound about nut member 24 and has its other 25 end secured to lever portion 23 such that the spring member 41 normally tends to pull the link 37 downward and the upper end of slot 38 into engagement with pin 39. Mounted rigidly on the top wall 30 is a power element 42 comprising an 30 hermetically sealed container 43 having a resilient wall 44 to which is secured a plunger 45 which extends downward through an aperture in the top wall 30 substantially over the shaft 17. Positioned between the resilient wall 44 and the 35 casing wall 30 is a coil spring 46 which surrounds plunger 45 and normally tends to move the same upwardly and to maintain the same in a raised position. Secured rigidly on the free end of plunger 45 within the casing 20, is a holding 40 means 47, preferably a hook member, which extends downward adjacent to and slightly below a side edge of the carrier member 14 to the rear of arm 36, and has a substantially horizontal arm 48 projecting beneath the carrier member 14 between arm 36 and means 12. The member 14 has 45 secured thereto, between arm 36 and means 12, an angle plate member 49 with a depending flange 50 which cooperates with and is engageable by the hook arm 48. The top or end wall 51 of container 43 has secured thereto and opening therethrough, one end of a tube 52 which is sealed at its free end, as at 53, and which is wrapped or coiled about the outlet pipe 7 in heat conducting relation thereto. The tube 52 and container 43 50 are charged with a volatile liquid so that the element 42 and tube 52 comprise a temperature responsive means or thermostat. One terminal of the motor 10 preferably connects directly to an electric main or supply line by a lead 54, while 55 the other lead 55 from the supply line connects to one terminal of the control means 12. The remaining terminal of the motor 10 and the other terminal of means 12 are connected together by a lead 56, so that the motor 10 is in series circuit 60 with the control means 12.

The operation of my device as embodied in a unit heater system, is as follows: When the element 5 has been heated by steam or other heating medium supplied by pipe 6, the outlet pipe 7 65 will have its temperature raised. When the tem-

perature of element 5 has been raised to a predetermined degree at which the temperature of the outlet pipe 7 will be at, say, about 160° F., then the volatile liquid in the coiled tube or bulb 52 will have expanded, exerting sufficient pressure to overcome the resistance of spring 46 and move the holding means 47 downward. As the hook arm 48 of means 47 is moved downward, the light spring 41 acting through link 37 will tilt or rock the control means or switch tube 12 clockwise of Fig. 2 on its fulcrum 17 to make contact between leads 55, 56 and start the fan motor 10. Downward movement of link 37 is permitted by the pin and slot connection between the link 37 and lever 21, and when arm 48 is completely depressed by the power means 42, the upper end of slot 38 will be in engagement with pin 39 and be so held by spring 41. Operation of motor 10 will drive fan means 3 to draw air from the space to be heated in through the bottom of casing 1, over 20 or in contact with the heater element 5 and discharge the heated air through the ducts 2. The fan means 3 will also draw air into the casing 1 through the inlet aperture 35 which air will flow over the power means 32. When the temperature 25 of the air passing over means 32 has been raised by the heated air discharged from ducts 2 to a predetermined degree—say, 70° F., then the pressure of the volatile liquid in means 32 will have built up sufficiently to overcome the resisting 30 force of springs 29 and 31 and will move lever means 21 upward. As lever means 21 moves upward, the pin 39 which is in engagement with the upper end of slot 38 will lift the link 37 and tilt or rock the switch tube or control means 12 35 counter-clockwise to the position of Fig. 2 to break the circuit of fan motor 10 and stop the further discharge thereby of heated air through ducts 2. Should the temperature of the air surrounding casing 1 now fall to, say, 68° F., the 40 pressure within means 32 will have decreased sufficiently to permit springs 29 and 31 to move lever means 21 downward, which movement will be transmitted to link 37 by spring 41 and tilt the switch tube 12 to make contact and again start 45 the fan motor 10. If during the operation of the fan motor 10 the temperature of the heater element 5 decreases below the desired temperature 50 so that the temperature of outlet pipe 7 becomes less than the predetermined temperature of 160° F., then the spring 46 will act upon reduction of pressure in container 43 and tube 52 to raise the hook member 47. As member 47 moves upward, arm 48 will engage flange 50 and tilt the switch tube 12 to the position of Fig. 2, thus breaking 55 the fan motor circuit and will hold or maintain the means 12 in circuit breaking position, irrespective of operation of lever means 21. The upward force of spring 46 acting on means 47 to tilt the means 12 to circuit breaking position, need 60 only be sufficient to overcome the light spring 41, as the springs 29 and 30 do not resist upward movement of means 47 by reason of the pin and slot, or lost motion connection between link 37 and lever means 21.

Although I have shown and described my control device as embodied in a unit heater system, it is to be noted that the same is capable of use in other systems wherein it is desired to control a motor means in response to variations of temperature or pressure, and to prevent operation of the motor means in response to a predetermined condition.

This application is a division of my copending 70 75

application Serial No. 501,927 filed December 12, 1930, now Patent 1,992,155, Feb. 19, 1935.

What I claim and desire to secure by Letters Patent of the United States is:

5 1. A device of the character described, comprising a casing, switch means in said casing, automatically operable power means for actuating said switch means, means interconnecting said power means and said switch means, spring 10 means urging said switch means to circuit breaking position, said connecting means including a lost-motion connection whereby to permit operation of said switch means by said spring means, and automatically acting responsive means oper- 15 able to overcome said spring means whereby to permit operation of said switch means by said power means.

2. A device of the character described, comprising a casing, switch means in said casing, 20 automatically operable power means for actuating said switch means, means interconnecting said power means and said switch means, a helical coil spring under compression and acting upon expansion to move said switch means to circuit 25 breaking position, said connecting means including a lost-motion connection whereby to permit operation of said switch means by said spring means, and automatically acting responsive means operable to compress said spring means 30 whereby to permit operation of said switch means by said power means.

3. A control device of the character described, comprising a carrier member having a fulcrum support, a switch tube supported by said member and tiltable about said support, automatic 35 means operable to tilt said tube to make and break circuit, means operable to engage said carrier member to tilt said tube, and a resilient connection operatively connecting said automatic 40 means and said member and yieldable whereby said last-named means may tilt said tube in opposition to said automatic means.

4. A control device of the character described, comprising a carrier member having a fulcrum support, a switch tube supported by said member and tiltable about said support, automatic 45 means operable to tilt said tube to make and break circuit, a hook member operable to engage said carrier member to tilt said tube and having means normally acting thereon to tilt said tube, and temperature responsive means operable 50 to overcome said last-named means to permit operation of said tube by said automatic means.

5. A control device of the character described 55 comprising a movable switch for controlling an electric circuit, means operable to move said switch to make and break circuit, means operable to move said switch to and hold said switch in a predetermined circuit controlling position, a lost-motion connecting member connecting said first-named means and said second-named means so that said second-named means can move said switch to said predetermined position irrespec- 60 tive of the operation of said first-named means, means operable to overcome said second-named means, and resilient means operatively connecting said first-named means and said switch for transmitting movement from said first-named 65 means to said switch, said resilient means being held under tension by said second-named means when said switch is held in said predetermined position and having a force stored therein operable to move said switch to another position upon 70 the overcoming of said second-named means.

6. A control device of the character described comprising switch means, automatically operable power means for actuating said switch means, spring means urging said switch means to circuit breaking position, means connecting said power means and said switch means, said connecting means including a lost-motion connection whereby to permit operation of said switch means by said spring means, an automatically acting responsive means operable to overcome said spring means 10 means to permit operation of said switch means by said power means, and spring means operatively connecting said switch means and said power means, said last-named spring means being held under tension by said first-named spring 15 means when the switch means is in circuit opening position and having a force stored therein operable to move said switch means to circuit closing position upon the overcoming of said first-named spring means. 20

7. In a device of the character described, a supporting means, a movable switch means supported by said supporting means, automatically operable power means for actuating said switch means, yieldable means operable to directly act on and move said switch means to and maintain said switch means in a predetermined position, means operable to overcome said yieldable means, and yieldable means operatively connecting said power means and said switch means and yieldable so 30 that said first-named yieldable means is operable to move said switch to said predetermined position irrespective of the operation of said power means, said last-named yieldable means being held under tension by said first-named yieldable 35 means when said switch means is maintained in said predetermined position and having a force stored therein operable to move said switch means to another position upon the overcoming of said first-named yieldable means. 40

8. In a device of the character described, a casing, switch means movably supported in said casing, a lever member fulcrumed in said casing and having a pin, a power element for operating said lever member, a connecting link connecting said lever member and said switch means, said link having a slot for receiving the pin of said lever member to provide a lost-motion connection between said link and said lever member, a spring means acting to maintain operative connection 50 between said lever member and said link, yieldable means operable to move said switch means to a circuit opening position without transmission of said movement to said lever member, said yieldable means placing said spring means under 55 tension exerting a force tending to move said switch means to circuit closing position, and automatically operable power means operable to overcome said yieldable means to release the force of said spring means for moving said switch 60 means to closed circuit position and to permit operation of said switch means by said first-named power means.

9. A control device of the character described comprising a movable controlling means, movable 65 holding means operable to hold said controlling means in one position and movable so that said controlling means can move to another position, power means for moving said holding means, power means operable to move said controlling 70 means, lost motion connecting means operatively connecting said second-named power means and said controlling means, and spring means acting through said lost motion connecting means to move said controlling means and held inactive by 75

said holding means when said holding means is holding said controlling means in said one position.

10. A control device of the character described
5 comprising a movable controlling means, movable holding means operable to move said controlling means in one direction and hold said controlling means in one position, power means operable to move said holding means out of holding
10 relation with said controlling means, power means operable to move said controlling means in said one direction and hold said controlling means

in said one position, lost motion connecting means operatively connecting said second-named power means and said controlling means, and spring means operable on movement of said holding means out of holding relation with said controlling means to move said controlling means to another position, said spring means acting on said controlling means through said lost motion connecting means and operable to establish positive connection between said second-named power 10 means and said controlling means. 5

EARNEST J. DILLMAN.
